UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

SAVINGS-BANK.

1,126,643.

Specification of Letters Patent.

Patented Jan. 26, 1915.

Application filed January 19, 1914. Serial No. 813,076.

To all whom it may concern:

Be it known that I, ISIDOR J. KUSEL, a citizen of the United States, residing at Chicago, in the county of Cook and State of Illinois, have invented a certain new and useful Improvement in Savings-Banks, of which the following is a full, clear, concise, and exact description, reference being had to the accompanying drawings, forming a part of this specification.

My invention relates to savings banks and especially to a form of savings bank adapted for small coins and to be carried in the pocket.

Prominent objects of the invention are to provide a simple, practical and inexpensive type of savings bank; to materially reduce the cost of manufacture of the same; to arrange for the easy and quick opening of the bank to extract the coins; to secure safety and prevent accidental opening of the bank and taking out of the coins before the bank is opened, or while being carried by the owner; and to secure other desirable results in a simple and expeditious manner.

In the accompanying drawings Figure 1 is an elevation of a bank embodying my present invention; Fig. 2 is a similar view showing the bank being opened; Fig. 3 is a cross sectional view of the bank on an enlarged scale.

The bank shown in the drawings, comprises a body portion, and a bottom 2, and top 3. The body portion 1 is desirably made of metal spun into a substantially cylindric form. The bottom 2 incloses or clasps the body and may be made detachable from the same. The top 3 detachably engages or clasps the upper edge of the body 1, and serves as a closure for the bank, inasmuch as the main body portion 1 has an open top. Thus it will be seen that when the top 3 is in place the bank is closed so as to prevent removal of coin. A small coin slot 6 is formed in one side of the bank and provided with a spring 7 to prevent the escape of coin from the bank, but to permit coin to be inserted into the same.

A key 8 is provided with a prong 9 adapted to fit into the side aperture 10. The key 50 8 is also provided with an end portion 11 adapted to engage the lid or cover of the bank, to pry the same off when said key is turned. This forms a very simple and practical device for quickly and easily opening 55 the bank, the prong 9 simply being inserted into the aperture 10 and then the key being given about a quarter turn more or less to pry off the cover.

In Fig. 3 I show the bank composed of a 60 ring or band shaped member, with small projections 12 around its edges, and covers fitted over said edges and held detachably in place by said projections. This is a very simple and inexpensive form, and particularly 65 advantageous, because either cover can be removed to open the bank.

It will be understood that changes and modifications can be made without departing from the invention. It will also be understood that different kinds or forms of 70 tools can be used for opening the bank.

What I claim is:

1. A device of the class specified comprising a box having an aperture, a cover fitting 75 over a portion of said box in combination with a key having a prong adapted to be inserted in said aperture from the outside of the box, and also having a shoulder adapted to engage a portion of said cover outside 80 of said box, so as to permit the removal of said cover.

2. A bank device comprising a body portion and separable top and bottom members, said body portion having an aperture, in 85 combination with a key having a prong adapted to enter said aperture and having a shoulder adapted to engage either of said top and bottom members.

In witness whereof, I hereunto subscribe 90 my name this 5th day of January A. D., 1914.

ISIDOR J. KUSEL.
